UNITED STATES PATENT OFFICE.

JOHN H. MOLONEY, OF PHILADELPHIA, PENNSYLVANIA.

LATERAL-SPACING ATTACHMENT FOR TYPE-WRITING MACHINES.

1,246,638.

Specification of Letters Patent.

Patented Nov. 13, 1917.

Application filed July 31, 1914. Serial No. 854,295.

To all whom it may concern:

Be it known that I, JOHN H. MOLONEY, a citizen of the United States, residing in Philadelphia, Pennsylvania, have invented 5 certain Improvements in Lateral-Spacing Attachments for Type-Writing Machines, of which the following is a specification.

My invention relates to typewriting machines, and consists of means intended and 10 designed more particularly for use in the operation of such machines when they are employed for filling in the superscription (name, address and salutation) on duplicate letters, (mimeographed or otherwise prepared); addressing envelops, postal cards, 15 labels, tags, &c., and for filling in reference cards.

My invention comprises means designed 20 to limit the rotative movement of the platen to effect the desired placement or positioning of the letter when commencing the superscription, dating, &c.

While the improvements forming the subject of my invention have been applied to 25 and are shown in connection with an L. C. Smith Bros. visible typewriting machine of the L. C. Smith Bros. make, it will be understood, that with but slight modifications, involving no change in the object, purpose or scope of the invention, they may be 30 applied to typewriting machines of all other manufacturers.

These and other features of my invention are more fully described hereinafter, reference being had to the accompanying drawings, in which:

Figure 1, is a perspective view of sufficient 40 of a type-writing machine to illustrate the application of my improved mechanism thereto;

Fig. 2, is a plan view of my improved mechanism;

Figs. 3 and 4, are front and end elevations of the same, respectively;

Fig. 5, is a view similar to Fig. 1, illustrating a modified structure within the scope 45 of my invention;

Fig. 6, is a plan view of the structure shown in Fig. 5, and

Figs. 7, 8, 9, 10 and 11, are views illustrating details of my invention.

Combined with the usual shaft or spindle 1 of the platen 2, which is mounted in the usual carriage (not shown), is a shaft extension 1^a, carrying a disk 3, of a special character, fixed to rotate therewith, which

disk is notched at its edge as at 4, while the shaft extension carries a plurality of loose arms 5, 5^a and 5^b, each having a spring-controlled pivoted finger 6, 6^a and 6^b, respectively; each of which fingers is arranged to be moved into and out of any one of said notches, as may be desired. The arms, 5, 5^a and 5^b are each maintained from longitudinal movement on the shaft by means of a 65 collar, 30 or other appropriate means, but said arms are free to drop by gravity when the fingers are disengaged from the notches of the disk whereby unlimited rotation of the platen is permitted. The fingers 6 and 6^a project beyond said disk 3 toward the platen and form stops to limit rotative movement of the platen; engaging with a member 70 hereinafter described, while the end of the finger 6^b lies substantially flush with the 75 face of the disk toward the platen and serves as a visible guide for the operator. The stop finger 6 limits the movement of the platen in the direction of the arrow *a*, after a duplicate (mimeographed) letter or other object 80 to be written upon has been positioned thereon, in order that it may receive the date, and the superscription, address, or the like, in the proper positions, and the stop 6^a limits the movement of the platen in the opposite direction, indicated by the arrow *b*, 85 after the superscription, salutation or other matter has been written.

The stops effected by the fingers 6 and 6^a are at the limits of the movement desired to 90 be given to the platen and any letter thereon; the letter being in position to receive the date when the stop 6 is in action, and in position to receive the salutation when the stop 6^a is in action. The arm 5^b is also 95 loose on the shaft extension 1^a and is preferably disposed between the arms 5 and 5^a. It carries the finger 6^b, which does not project beyond the inner surface of the disk 3 but forms a visible guide or indicator for 100 the operator and is designed to indicate the point on the letter where the first line of the superscription is to be written.

Carried by the shaft 1 or shaft extension 1^a and disposed inside the disk 3, is a non-rotating relatively fixed disk member 7, having a pair of arms 8 and 9 whereby it may be disposed in relatively fixed position with relation to the carriage of the machine and having a projection 10 at its peripheral edge 110 for engagement by the stops 6 and 6^a of the structure shown in Figs. 1, 2, 3 and 4;

the stop 6 engaging the upper surface while the stop 6^a engages the lower surface of the same. The arm 8 is preferably positioned with respect to the carriage by means of a set screw 11 and lock nut 12, while the arm 9 may also engage a portion of the carriage, as indicated in the drawings.

In lieu of mounting a plurality of arms on the shaft extension 1^a, the disk may be 10 of the character shown at 2^a in Figs. 5 and 6, and carry directly a spring-controlled pivoted finger 6^c forming a stop to limit movement of the platen in the direction of the arrow b; otherwise effected by the finger stop 6^a; the shaft extension 1^a carrying a loose arm 5 with a stop finger 6; such fingers 6 and 6^c having the same function as the fingers numbered 6 and 6^a in the structure shown in Figs. 1, 2, 3 and 4.

20 The fingers 6, 6^a and 6^b, of the structure shown in Figs. 1, 2, 3 and 4, bear the following relation: When the letter is to be inserted, the usual paper grips carried by the machine are released, permitting the 25 letter to be inserted and positioned at any point on the platen. For this purpose the platen is moved rearwardly on its axis in the direction of the arrow b until the stop 6^a comes into engagement with the under 30 side of the projection 10 carried by the disk member 7, as shown in Fig. 1. The letter is then inserted in the machine for movement by the platen and the first line of writing properly positioned with respect to 35 the scale bar and then the platen is moved forward, in the direction of the arrow a so as to bring the finger guide 6 into contact with the upper side of the projection 10. The letter sheet will then be in proper position 40 to receive the date. The platen is then rotatably moved a sufficient amount to bring the guide finger 6^b opposite the upper side of the projection 10, when the letter sheet will be in proper position to receive 45 the name portion of the superscription. The distance on the platen between the stops may be anything desired, and the notches of the disk correspond exactly with the positions of the platen as determined by the 50 spaces between the ratchet teeth of the same.

In the use of the structure shown in Figs. 5 and 6, the fingers 6 and 6^c contact with the frame of the carriage to limit the rotative movement of the platen.

55 A detail view of the finger 6 or 6^a, partly in section, is shown in Fig. 9; a detail view of the finger 6^b, partly in section, is shown in Fig. 10, and a detail view of the finger 6^c, partly in section, is shown in Fig. 11. 60 The fingers are arranged to be retained in their respective positions by suitable retaining means consisting of the balls 13 and springs 14.

In order to position the letter laterally

with respect to the platen and the typev ten or otherwise applied matter on the ter, a stop ring or guide 15 may be mou on the platen, said stop ring being prov with a straight face 16 disposed at r angles to the platen and against which left edge of the letter sheet must be pla The distance from the stop ring represing the margin of the paper, and the 1 tion of the matter appearing thereon is course, known, and the various adjustm of the machine are set so that the first ter of the person's name forming part the superscription will be directly in with the first letters of the several line the duplicate (mimeographed) letter. stop ring may be sprung into place and preferably slotted as shown at 17. springing it slightly apart, it may be rea adjusted in any suitable position on platen. Instead of springing it into pl however, the platen may be provided wi threaded portion 18 to receive a threa stop ring 15^a, shown in Fig. 8.

The position the first line of the su 25 subscription is to occupy with respect to rest of the sheet is, of course, readily de mined by gaging the first line of the r ter on the paper with respect to the u scale bar (not shown) mounted on the riaje of the machine. It is known, of cou how many lines the subscription is to copy, and with this knowledge the piv finger 6 is thrown into a notch of the di to represent one end of the limit of the tative movement of the platen; the notches being spaced in accordance with platen spacing, and the platen is then tui until the other end of its limited moveme determined and the finger 6^a is moved engagement with one of said notches, thereby the limit of rotative movemen said platen in both directions is fixed. lieu of using the finger 6, the guide fi 6^b may be employed; the operator wa ing its position when moving the plate bring the letter to position to commence writing of the superscription. The fi 6^a may serve as a stop to position the line, and if desired either this finger or guide finger 6^b may be put out of act the fingers 6 and 6^c being usable alone the fingers 6 and 6^b, or the fingers 6^a and as may be desired by the operator; it b understood that the finger 6^b is a guide not a stop.

In order to effect stoppage of the car and platen when moved longitudinally effect desired lateral spacing of the port of the superscription, the extension 1 the platen shaft 1 may carry a pluralit fingers 20, 20^a, and 21, 21^a, which are ranged to contact with a relatively 1 stop 22 adjustably mounted in a bra

- 23 carried by the frame of the machine and held in place by a set screw 24; said bracket being slotted at 25 to permit the desired adjustment of said stop 22. When the carriage is moved into position by the operator before commencing a line of writing, one of the fingers 20, 20^a, 21, or 21^a, in line with said stop 22, will engage the same and limit such movement.
- 10 These fingers 20, 20^a, &c., are adjustable for any position. The fingers 20 and 20^a may be employed to control the position of the platen for the lateral spacing of the superscription on a letter, while the fingers 15 21 and 21^a may be employed to control the position of the platen for the lateral spacing of the address on a postal card, envelop, or the like.
- 20 In operation, a sheet of paper (the duplicate letter) is slipped into place with the platen moved back in direction of arrow *b* with stop 6 in engagement with the projection 10 (or the frame of the carriage) and with paper grips out of action. As before noted, the position of the first line of the superscription is adjusted with respect to the scale bar, and then, after the paper grips have been released to engage the paper, the platen is rotated in direction of arrow *a* 30 to bring the stop 6^a (or 6^c) or guide 6^b in contact or operative position with respect to the other side of the projection 10 (or the frame of the carriage). The carriage with the platen is then moved longitudinally to the proper initial position and the first line is written. The carriage is then shifted for the second line; the platen being simultaneously rotated to position the letter to receive such second line and then the finger 40 20 on the shaft extension 1^a will come into action; such finger being set so as to occupy a definite relation with respect to the second line of the superscription, and upon longitudinal movement of the carriage it contacts with the fixed stop 22. This second line of the superscription is written, and when this is completed the carriage is again shifted and the platen moved simultaneously therewith, and when brought to the proper 50 position the second finger 20^a comes into position to space the third line of the superscription at the proper point, and then when the carriage is shifted the third time the fingers 20 and 20^a are clear and the carriage 55 may be brought to a position in line with the name for the insertion of the salutation: "Dear Sir", "Gentlemen", or the like. At this position, the stop 6^a is in contact with the projection 10 (or the frame of the carriage) and it is impossible to impart further 60 rotative movement to the platen. The operator then releases the paper grips, withdraws the sheet, inserts a new one and proceeds as before. It will be understood, of course, that any number of fingers 20, 20^a, 65 &c., may be used, as desired, depending upon the number of lines in the superscription, address and salutation.
- When addressing postal cards or envelopes, I may use a holder 26 carried by the platen. 70 The holder is preferably provided with end portions 27 forming clips to engage and hold the edge of the card or envelop and the position of these clips is in definite relation to the stop formed by the finger 6^a so that when the platen is moved in the direction of the arrow *a* and stopped by the finger 6, or stopped by the operator, as indicated by the guide 6^b, the postal card or envelop will be in proper position to receive the first line 80 of the address or name of the addressee. When the carriage and platen are shifted for the second line of the address, the longitudinal movement of the carriage will be halted by the finger 21 engaging the stop 85 22 at a point, five, (more or less, as desired,) letter spaces short of the commencement of the first line, and the stop 21^a will effect a stoppage at a point, five, (more or less) letter spaces short of the commencement 90 of the second line, and so on. It will be understood that this holder 26 may be of any length, accommodating letter sheets, cards, envelops and the like, and that it is carried by the platen so as to properly position the element engaged thereby with respect to the fingers 6, 6^a, 6^b, or 6^c, as the case may be.
- 25 The shaft extension 1^a carrying the fingers 20, 20^a, &c., is scaled so as to agree with the markings of the scale bar of the carriage. In some instances, pairs of the fingers may be combined in a single element when the lateral spacing of the lines of the superscription or address is uniform. 100 These fingers 20, 20^a, &c., are adjustable for any arrangement of spacing, and may be held in their adjusted positions by set screws 29.
- 30 It will be understood, of course, that the stop mechanism controlling the rotative movement of the platen may be released by removing the several fingers from engagement with the notched disk or moving them out of their projected position beyond the 110 inner face of the latter, and that when this is done the platen is free to continuously rotate in the usual use of the typewriting machine. At the same time, the stop 22 may be moved out of the way so that engagement of the same by the fingers 20, 20^a, 21 and 21^a will be avoided.
- 35 I claim:
1. The combination, with the platen of a typewriting machine, and a shaft in axial alignment therewith, of a notched disk carried by said shaft and rotating therewith, the notches of said disk bearing an exact

relation to the line spacing positions of the platen, an arm on said shaft outside the disk and maintained from longitudinal movement on the shaft and a finger pivotally mounted in the outer end of said arm having engagement with any one of said notches, said finger projecting beyond the face of the disk and arranged to contact with a part fixed with respect to the frame of the carriage and forming a stop for limiting the rotative movement of the platen, said arm being freely rotatable on said shaft whereby it will drop by gravity when said finger is disengaged from the notches of the disk, to thereby permit the unlimited rotation of the platen.

2. The combination, in a typewriting machine, of a platen, a shaft therefor, a notched disk carried by said shaft and rotating therewith, an arm on the shaft maintained against longitudinal movement thereon, a finger pivotally mounted in the end of said arm for engagement with said notches, said finger projecting beyond the face of the disk and forming a stop limiting the rotative movement of the platen in one direction and being movable to a position to free it from engagement with said disk whereby the arm will drop by gravity and unlimited rotative movement of the platen is permitted, and a second finger pivotally mounted and projecting beyond the face of said disk and serving when in such position to limit the movement of the platen in the opposite direction, said second finger being movable out of the stop engaging position.

3. The combination, in a typewriting machine, of a platen, a shaft in axial alinement therewith, a notched disk carried by said shaft, and an arm loose on the shaft and maintained against longitudinal movement on said shaft, a finger pivotally connected to said arm and arranged to engage any one of the notches of the disk, said finger forming a stop for limiting the rotative movement of the platen in one direction, and said arm being permitted to drop by gravity when the finger is disengaged from the notch of the disk, whereby unlimited rotation of the platen is permitted, and a second pivotally mounted finger serving to limit the rotative movement of the platen in the opposite direction, said second finger being movable to non-stopping position to permit the continuous rotation of the platen.

4. The combination with a typewriting machine having a platen and a shaft in axial alinement therewith, of a notched disk carried by said shaft, a plurality of arms loose on the shaft and each maintained against movement lengthwise of said shaft, a finger pivotally connected to one of said arms and arranged for engagement with any one of the notches of said disk, said finger project-

ing laterally beyond the disk and forming a stop for limiting the movement of the platen in one direction by engagement with an element fixed with respect to the carriage frame of the typewriting machine, and a second finger pivotally connected to one of the other arms and arranged for engagement with the notches of the disk and to project beyond the face of the latter whereby it may serve as a stop to limit the movement of the platen in the opposite direction by engagement with an element fixed with respect to the carriage frame, said arms being free to drop by gravity when their respective fingers are disengaged from the notches of the disk whereby unlimited rotation of the platen is permitted.

5. The combination with a typewriting machine, of a platen, a shaft in axial alinement and movable therewith, a notched disk carried by and rotatable with said shaft, a plurality of arms loosely mounted on the shaft and disposed at one side of said disk, each of said arms being maintained against movement lengthwise of the shaft, and fingers pivotally connected to said arms and arranged for engagement with the notches of the disk, certain of said fingers projecting beyond the face of the disk and forming stops or limiting the rotative movement of the platen in opposite directions, said arms being free to drop by gravity when their respective fingers are disengaged from the notches of the disk whereby unlimited rotation of the platen is permitted.

6. The combination, in a typewriting machine, of a carriage, a shaft carried thereby, a notched disk carried by and rotating with said shaft, a plurality of arms loosely mounted on the shaft and maintained from movement longitudinally thereof, fingers pivotally carried by said arms for engagement with the notches of said disk, said fingers forming stops for limiting the movement of the platen in opposite directions, said arms being free to drop by gravity when their respective fingers are disengaged from the notches of the disk whereby unlimited rotation of the platen is permitted, and means carried by the shaft but fixed against movement therewith for engagement with said fingers to limit the rotative movement of the shaft in both directions.

7. The combination, in a typewriting machine, of a carriage, a shaft carried thereby, a platen mounted on said shaft, a notched disk carried by said shaft beyond the platen, a plurality of arms loose on said shaft, but maintained against movement lengthwise thereof, said arms being disposed adjacent the disk on the side beyond the platen, fingers pivotally mounted on each of said arms and movable into and out of engagement with the notches of the disk, said

fingers when in engagement with the disk projecting beyond the face of the same and forming movable abutments, said arms being free to drop by gravity when their respective fingers are disengaged from the notches of the disk whereby unlimited rotation of the platen is permitted, a stop member disposed adjacent the notched disk and having a projection for engagement by said fingers to stop the rotative move-

ment of the platen, and means for holding said stop member in fixed position with respect to the carriage.

In testimony whereof, I have signed my name to this specification, in the presence 15 of two subscribing witnesses.

JOHN H. MOLONEY.
